UNITED STATES PATENT OFFICE.

JAMES M. CUNNINGHAM, OF LEWISBURG, WEST VIRGINIA, ASSIGNOR OF
ONE-HALF TO JOHN F. ESTILL, OF SAME PLACE.

ADJUSTABLE BIT.

SPECIFICATION forming part of Letters Patent No. 411,953, dated October 1, 1889.

Application filed September 26, 1888. Serial No. 286,463. (No model.)

To all whom it may concern:

Be it known that I, JAMES M. CUNNINGHAM, a citizen of the United States, residing at Lewisburg, in the county of Greenbrier and State of West Virginia, have invented new and useful Improvements in Adjustable Bits, of which the following is a specification.

The invention relates to improvements in adjustable bits to be used with mortising-machines and adapted to cut tenons of different sizes; and it consists in the construction and novel combination of parts hereinafter described, illustrated in the accompanying drawings, and pointed out in the claims.

15 In the drawings, Figure 1 is a perspective view of a bit embodying the invention, which bit is made in two sections. Fig. 2 is a perspective view of the smaller section of the bit. Fig. 3 is a rear elevation of the bit.

20 Referring to the drawings by letter, A designates the larger section of the bit provided with the leg B, having a beveled cutting-edge b at its end. The said section has the body C and the neck c for insertion in the chisel-rod of any mortising-machine, the body having a straight lower edge c', that stands at right angles to the leg B.

25 D is the second or smaller section of the bit, composed of a leg E, similar to the leg B, and having a similar beveled cutting-edge e, and the two parallel arms F G, standing at right angles to the leg, the arm F extending from the upper end of the leg and the arm G from a point a suitable distance below the former. The said arms F G are respectively provided with the longitudinal slots f g, and move in the grooves H and I in the leg B, the former of which is adjacent to the straight edge c' and the latter below it.

h and i are threaded openings in the grooves 40 H and I, and J and K are set-screws passing through the slots f and g and engaging said openings. By means of said slots and screws the legs D and E, which have their cutting-edges aligned, can be moved nearer together 45 or farther apart to cut tenons of different widths.

The meeting edges of the body C and arm F are preferably rabbeted at L, where they are fitted together. 50

The operation of the bit is obvious, as it may be used with any style of mortising-machine, and will cut tenons of any desired length or width.

Having described my invention, I claim— 55
1. The combination, with the section A, having the leg B and provided with the grooves H and I, of the section D, having the leg E, provided with the slotted arms F and G, and the set-screws J and K, substantially 60 as described.

2. In a bit, the combination, with the section A, having the leg B, provided with the bevel cutting-edge b, the body C, the neck c, and the slots H and I, of the section D, having the leg E, provided with the cutting-edge e and the slots f and g in its arms F and G, and the set-screws J and K, substantially as 65 described.

In testimony that I claim the foregoing as 70 my own I have hereto affixed my signature in presence of two witnesses.

JAS. M. CUNNINGHAM.
